PUMP PISTON

Application filed August 4, 1930. Serial No. 473,081.

This invention relates to pump pistons and more particularly to pistons which are adapted for use in slush pumps or other pumps handling fluids in which are contained abrasive materials.

In the oil-producing industry a slush pump is employed to provide a rotary fluid to the bit during drilling operations. In order to secure the proper circulation it is necessary that this fluid should be subjected to a very high pressure. The rotary fluid is in the form of a thin mud and there is a very large content of abrasive materials. Because of the high pressure required and the large content of abrasive materials carried by the rotary fluid, the wear on the pistons of the slush pumps is very great so that after a short period of operation it is necessary to mechanically adjust the piston into proper contact with its cylinder wall.

It is an object of my invention to provide a piston which is self-adjusting and will automatically be maintained in proper contact with the wall of the cylinder in which it operates.

In accordance with this purpose I have provided a pump piston formed of a resilient material, such as rubber, with end plates which are adapted to exert an axial pressure on the ends of the piston to expand it radially into the desired working contact with the wall of the cylinder.

If the contact between the ends of the piston and the cylinder wall is such that there is no leakage of the fluid, there is but little wear on the middle part of the piston. In order to establish such a contact I provide a piston body of resilient material having end portions which are retained in proper working contact with the cylinder by the fluid pressure within the cylinder.

If the fluid in such pumps is permitted to come into contact with the ends of the piston formed of resilient material, I have found that the ends of the piston are rapidly worn away.

It is an object of this invention to provide a pump piston in which the resilient body will be protected from direct contact with the fluid being pumped and consequently from

the greater part of the abrasive action of the fluid.

I have found that if the movement of the end plates toward each other to accomplish the desired radial expansion of the piston body is restricted only by the inherent resistance to deformation of the resilient body, it is possible for the piston body to be so expanded radially by the pressure on its ends that it becomes frozen in the cylinder.

It is a further object of this invention to provide a pump piston of the class described having means for limiting the movement of the end plates toward each other and thus limiting the axial pressure on and radial expansion of the piston body.

Other objects and advantages will be pointed out in the following description in which reference will be had to the accompanying drawing.

In the accompanying drawing, in which a preferred and an alternative form of my invention are illustrated:

Fig. 1 is an elevational view.

Fig. 2 is a cross-section of the preferred form of the piston of my invention installed in a pump cylinder.

Fig. 3 is a cross-section of the alternative form of the piston of my invention installed in a pump cylinder.

Fig. 4 is a sectional view taken as illustrated on the line 4-4 of Fig. 3.

Referring in detail to the drawing and particularly to Fig. 1, the numeral 11 indicates the resilient piston body of the piston 12 of my invention. The body 11 is preferably formed of rubber or rubber composition having good wearing qualities. A central portion 13 of the piston body 11 is cylindrical and of such a diameter that this portion of the piston body may be slidably disposed in the cylinder in which it is adapted to operate without deformation. The diameter of the piston body 11 at each of its ends is slightly greater than the diameter of the central portion 13 so that a lip 14 is formed at each end of the piston body 11 of such a diameter as to require some deformation when the piston 12 is installed in a cylinder.

As best shown in Fig. 2, the preferred form

of my invention is provided with a central cylindrical bore 15 of a diameter somewhat larger than the diameter of a reduced portion 16 of a piston rod 17 upon which the piston 12 of my invention is adapted to be installed.

Formed in each end of the piston body 11 is an inner concentric annular channel 18 and an outer concentric annular channel 19.

As is well illustrated in Fig. 2, the inner channel 18 is of a depth considerably greater than the outer channel 19 and the outer wall of the channel 19 is sloped to its intersection with the outer periphery of the lip 14.

Adapted to be placed upon the reduced portion 16 of the rod 17 are two end plates 20 and 21, each of which is provided with an outer hub portion 22. The hub portion 22 of the end plate 20 is adapted to abut against a shoulder 23, separating the reduced portion 16 from the remainder of the piston rod 17, and the hub portion 22 of the end plate 21 is adapted to be engaged by a nut 24 which is screwed onto a threaded end 25 of the reduced portion 16 of the piston rod 17.

Each of the end plates 20 and 21 has an inner surface 26 adapted to engage end faces 27 of the piston body 11. Projecting inwardly from the inner surface 26 of each of the end plates 20 and 21 is a compressing means 28 in the form of an inner concentric annular flange 28. The annular flanges 28 are adapted to be received in the channels 18 formed in each end of the piston body 11. As will be seen by reference to Fig. 2 of the drawing, the channel 18 and the cooperating flange 28 incline outwardly toward the center of the piston body 11 to a slight extent so that as the end plate 21 is moved toward the end plate 20 the flange 28 will exert a pressure upon that portion of the piston body 11 between the channel 18 and the central bore 15 tending to clamp the piston body 11 securely in place. Also formed on the inner surface 26 of each of the end plates 20 and 21 at the outer periphery thereof is an outer inwardly extending concentric annular flange 29 which is received in the outer channel 19. The flange 29 contacts only the inner surface 30 of the channel 19 so that the outer surface 31 of the channel 19 is exposed to contact the fluid contained within the cylinder 32.

In the preferred form of my invention, illustrated in Fig. 2, each of the end plates 20 and 21 is provided with a hollow cylindrical inwardly extending sleeve 33. The inner diameter of the hollow sleeves 33 is such that the end plates 20 and 21 may be slidably disposed upon the reduced portion 16 of the piston rod 17. The outer diameter of the sleeves 33 is such that the piston body 11 may be slidably positioned thereon. The sleeves 33 are made of such a length that when their inner ends contact each other the pressure exerted upon the end surfaces 27 of

the piston body 11 by the end plates 20 and 21 will be great enough to cause the piston body 11 to be radially expanded into working contact with the wall of the cylinder 32 but not great enough so that this radial expansion will be sufficient to cause the piston body 11 to become frozen and immovable in the cylinder 32.

The end plates 20 and 21 are installed upon the reduced portion 16 of the piston rod 17 with the piston body 11 positioned upon the sleeves 33 between the end plates 20 and 21, and the piston 12 is installed in the cylinder 32. Since the end lips 11 are under compression when installed in the cylinder 32, as previously explained, no fluid pressure exists between the said lips and the said cylinder. The fluid pressure on the exposed end of the piston body 11 forces the lips 14 into a fluid tight contact with the cylinder wall 32 thus preventing the abrasive content of the fluid being pumped from entering between the cylinder wall 32 and the piston body 14 and wearing the piston body 14. As the end plate 21 is moved toward the end plate 20 by screwing the nut 24 upon the threaded end 25 of the reduced portion 16 of the piston rod 17, the piston body 11 is subjected to axial pressure, which causes its radial expansion. The radial expansion of the piston body 11 causes the central portion 13 of the piston body 11 to be moved into working contact with the wall of the cylinder 32. When the desired radial expansion has been secured, a lock nut 34 is screwed onto the threaded end 25 of the piston rod 17 to hold the nut 24 in place. As the piston body 11 becomes worn it is possible to screw the nut 24 further upon the piston rod 17 so that the piston body 11 is subjected to a greater axial pressure and consequent radial expansion. The possibility that the radial expansion of the piston body resulting from the movement of the end plate 21 toward the end plate 20 may be such that the piston body 11 will become frozen in the cylinder 32 is obviated by the action of the sleeves 33 which contact each other and prevent further movement of the end plate 21 toward the end plate 20 before such excessive radial expansion is effected.

In that form of embodiment of my invention illustrated in Fig. 3, the form of the piston body 11 of resilient material differs from the form of the piston body 11 illustrated in Fig. 2 only in that the central cylindrical bore 35 of the piston body 11 is smaller, this bore 35 being adapted to permit the piston body 11 to be positioned directly upon the reduced portion 16 of the piston rod 17. The end plates 20 and 21 in this embodiment of my invention are exactly like the end plates 20 and 21, as illustrated in Fig. 2, with the exception that there are no sleeves 33 provided.

Embodyed in the piston body 11 between the inner channel 18, formed in either end of the piston body 11, and the central bore 35, are means for limiting the movement of the 6 end plates 20 and 21 relative to each other in the form of rods or bars 36. The rods 36 are positioned in the piston body 11 parallel to its axis and are equally distant therefrom. The rods 36 are of a length somewhat less 10 than that of the piston body 11, as illustrated in Fig. 3.

When the nut 24 is screwed upon the threaded end 25 of the piston rod 17 the end plate 21 is moved toward the end plate 20.

15 This movement of the end plate 21 toward the end plate 20 will be limited either by the contact between the end plates and the rods 36, or by the incompressibility of those elements of the piston body 11 represented by 20 the dotted lines 37 as being a continuation of the rods 36, depending upon the relative length of the rods 36 and the piston body 11. In that form of embodiment hereinbefore described the nut 24 is advanced on the 25 threaded end 25 of the piston rod 17 until the desired contact between the piston body 11 and the wall of the cylinder 32 is secured, at which time the lock nut 34 is advanced on the threaded end 25 of the piston rod 17 30 against the nut 24 to hold it in its proper position.

I claim as my invention:

1. In combination: a resilient piston body having end lips surrounding annular channels, and having a central opening through which a shaft may extend; metal end plates adapted to pressurally engage the ends of said resilient piston body; and rods supported in said body to limit the pressure exerted 40 on said body by said end plates.

2. In combination: a resilient piston body having a central opening through which a piston rod may extend, the opposite end walls of said body having a concentric channel defining an outer peripheral lip; end plates adapted to pressurally engage the ends of said resilient piston body, each of said end plates having a concentric flange extending inwardly into said channel leaving a portion 50 of said channel available for occupation by fluid under pressure to force said peripheral lip against the wall of the cylinder in which said piston body is adapted to operate; means for moving one of said end plates toward the other to axially compress and radially expand said piston body to working contact with the wall of said cylinder, and to further axially compress and radially expand said piston body to compensate for 55 wear; and rods supported in said body and extending parallel to its axis for a portion of its length for limiting the movement of one of said end plates toward the other.

3. In combination: a resilient piston body 60 having a central opening through which a

shaft may extend, the opposite end walls of said body having a concentric channel defining a peripheral lip adapted to be forced into working contact with the wall of a cylinder in which the said body operates by 70 fluid pressure against the outer wall of said channel; end plates adapted to engage the ends of said piston body with a variable pressure; and rods supported in said body parallel to its axis, said rods being of a 75 length less than the length of said body and adapted to limit the maximum pressure applied on said resilient piston body by said end plates.

4. In combination: a resilient piston body 80 having a central opening, the opposite end walls of said body having an outer concentric channel defining a peripheral lip adapted to be forced into working contact with the wall of a cylinder in which said body operates by fluid pressure against the outer wall of said channel, and an inner concentric channel defining an end hub; end plates engaging opposite ends of said piston body, each plate having an inner concentric flange 85 extending inwardly into the companion inner channel of said body to confine the adjacent end hub thereof, and an outer concentric flange at its outer periphery extending inwardly into and engaging the inner wall of 90 said outer channel; means for moving one of said end plates toward the other to axially compress and radially expand said body into 95 working contact with the wall of said cylinder, and to further axially compress and radially expand said body to compensate for wear; and rods supported in said resilient piston body parallel to its axis, and of a length less than the length of said body, to 100 limit the movement of one of said end plates 105 toward the other.

5. In combination: a piston rod; a piston 110 consisting of a resilient piston body having a central opening through which a shaft may extend, the opposite end walls of said body having formed therein an outer concentric channel defining an outer peripheral lip, and an inner concentric channel defining an end hub; end plates engaging opposite ends of 115 said piston body, each plate having a concentric flange extending inwardly into the companion inner channel of said body to confine the adjacent end hub thereof, and a second concentric flange on the outer edge of each end plate extending inwardly into said 120 outer concentric channel and leaving a portion thereof available as a pressure chamber; means for causing relative movement of said end plates toward each other whereby the resilient piston body will be axially compressed and radially expanded to working 125 contact with the wall of a cylinder in which it is adapted to operate, and to further axially compress and radially expand said resilient body to compensate for wear; and 130

control means for limiting the pressure applied to said resilient piston body by said last named means.

6. In combination: a piston rod; a piston consisting of a resilient body mounted on said rod; end plates engaging opposite ends of said piston body; means for causing relative movement of said plates toward each other to axially compress and radially expand said 10 resilient body to working contact with the wall of a cylinder in which it is adapted to operate, and to further axially compress and radially expand said resilient body to compensate for wear; and rods supported in said 15 resilient body to limit the pressure exerted on said body by said end plates.

7. In combination: a piston rod; a piston consisting of a resilient piston body having a central opening through which a shaft may 20 extend, the opposite end walls of said body having formed therein an outer concentric channel defining an outer peripheral lip, and an inner concentric channel defining an end hub; end plates engaging opposite ends of 25 said piston body with their entire inner surface, each plate having a concentric flange extending inwardly into the companion inner channel of said body to confine the adjacent end hub thereof, and a second concentric 30 flange on the outer edge of each end plate extending inwardly into said outer concentric channel and leaving a portion thereof available as a pressure chamber; means for causing relative movement of said end plates 35 toward each other whereby the resilient piston body will be axially compressed and radially expanded to working contact with the wall of a cylinder in which it is adapted to operate, and to further axially compress 40 and radially expand said resilient body to compensate for wear; and control means for limiting the pressure applied to said resilient piston body by said last named means.

In testimony whereof, I have hereunto set 45 my hand at Los Angeles, California, this 30th day of July, 1930.

CHARLES LAMB.
